Bluma Hutchinson, Brooklyn, N. Y.

Application July 14, 1954, Serial No. 31,425

Term of patent 14 years

(Cl. D47—2)

Fig. 1 is a face view of a knitted fabric or similar article, showing my new design. The full width of the fabric is disclosed vertically and the design unit is repeated horizontally in proper relation to complete the fabric;

Fig. 2 is an edge view of Fig. 1; and

Fig. 3 is an enlarged portion of Fig. 2, taken on line 3—3 of Fig. 1.

The dominant features of the design shown in the drawing reside in a series of herringbone sections repeated horizontally and separated by vertically disposed spaced threads, with a wavy wale intermediate the ends of said threads, and in the border of fringe-like formation including a horizontally disposed wavy wale adjacent its inner end and a horizontally disposed rope-like chain at its outer end.

I claim:

The ornamental design for a knitted fabric or similar article, as shown and described.
